US00D991829S

(12) **United States Design Patent** (10) **Patent No.:** **US D991,829 S**
Kentley-Klay et al. (45) **Date of Patent:** **** Jul. 11, 2023**

(54) **VEHICLE**

- (71) Applicant: **Zoox, Inc.**, Foster City, CA (US)
- (72) Inventors: **Timothy David Kentley-Klay**, Stanford, CA (US); **Nahuel Elias Battaglia**, Stanford, CA (US); **Herman Francisco Delos Santos**, Redwood City, CA (US); **Richard Luke Osellame**, Redwood City, CA (US); **Christopher John Stoffel**, San Carlos, CA (US)
- (73) Assignee: **Zoox, Inc.**, Foster City, CA (US)
- (**) Term: **15 Years**
- (21) Appl. No.: **29/868,302**
- (22) Filed: **Nov. 29, 2022**

Primary Examiner — Darlington Ly(74) *Attorney, Agent, or Firm* — Lee & Hayes, P.C.(57) **CLAIM**

The ornamental design for a vehicle, as shown and described.

DESCRIPTION

FIG. 1 is a front perspective view of a vehicle embodying our new design;

FIG. 2 is a front elevation view thereof;

FIG. 3 is a back elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

The broken lines illustrate portions of the vehicle that form no part of the claimed design. The dot-dashed broken lines illustrate boundaries of the claimed design and form no part of the claimed design.

1 Claim, 7 Drawing Sheets(56)
